JOHN J. GILBERT, OF DOUGLASTON, NEW YORK, ASSIGNOR TO WESTERN ELECTRIC COMPANY, INCORPORATED, OF NEW YORK, N. Y., A CORPORATION OF NEW YORK

LOADED SIGNALING CONDUCTOR

Original application filed March 5, 1924, Serial No. 696,981, and in France January 6, 1924. Divided and this application filed May 31, 1928. Serial No. 281,617.

This invention relates to long loaded submarine cables.

An object of the invention is to reduce impedance irregularities in a loaded cable.

5 Another object of the invention is to reduce signal distortion which results from variations in the impedance of the conductor with variations in the current flowing therethrough.

10 In long submarine cables the overall attenuation is so great that relatively large currents must be applied at one end in order that signals of suitable strength may be received at the distant end. If the conductor is loaded 15 with magnetic material the permeability and hysteresis losses of which vary with the magnetizing force, the large variations in the current and hence the magnetizing force in the terminal sections may cause the inductance and resistance due to the loading material to vary between wide limits. As a 20 result of these variations in the inductance and resistance of the conductor, it is difficult to construct an artificial line that will simulate such a cable with sufficient exactness for 25 duplex telegraph operation. If the cable is designed for telephone or carrier frequency operation there is the additional objection that the varying impedance produces inter- 30 modulation between different telephone and carrier frequencies with resultant distortion.

It is proposed, in accordance with this invention to reduce the variations in inductance and in effective impedance of the terminal 35 sections of a loaded conductor by reducing the amount of the loading material on those sections as compared to the loading on the sections of conductor more remote from the terminals.

40 This is a continuation as to certain divisible subject matter of J. J. Gilbert applications Serial No. 696,981, filed March 5, 1924, and Ser. No. 579,393, filed Aug. 3, 1922.

The invention will now be explained in 45 connection with the drawing, in which,

Fig. 1 comprises curves indicating the variations in the inductance and resistance of a loaded conductor with variations in the current flowing in the conductor;

50 Fig. 2 is a curve showing the intensity of

signaling current in a conductor at various points along its length;

Fig. 3 is a diagrammatic showing of how the loading may be tapered on a conductor in a duplex telegraph system, and

55 Figs. 4 and 5 disclose methods of reducing the amount of loading material on the terminal portions of the conductor.

It has long been recognized that loading a signaling conductor with magnetic material 60 will in general decrease the attenuation due to the distributed resistance and capacity of the conductor.

65 Objectionable characteristics may, however, result from the loading itself. For instance there is always introduced a certain amount of dissipation due to eddy current losses and hysteresis losses in the loading material. These losses are the more objectionable because instead of being constant they 70 increase with the current in the conductor. Likewise the permeability of the loading material varies with the current. Hence, whereas an unloaded conductor may have substantially constant resistance and inductance for 75 all intensities of current that may be transmitted thereover, the effective resistance and inductance of a loaded conductor may increase rapidly with an increase in current.

These variations in the inductance and 80 effective resistance of a loaded conductor when traversed by currents of different intensities are of course different in degree for different loading materials. The variations in a conductor loaded with a particular alloy containing about 80% nickel and the balance chiefly iron when heat treated to give a high initial permeability are shown in Fig. 1 of the drawing.

85 On a telegraph cable operated duplex these characteristics of a loaded cable become particularly objectionable because it is very difficult and expensive to build an artificial line that will have the same variable resistance and inductance characteristics as the loaded cable. On a telephone conductor impedance 90 variations with the current variations are objectionable because they produce intermodulation of the different frequency waves comprising the speech spectrum, or different 95 100

speech channels, with resultant distortion of the speech.

In general the objectionable characteristics resulting from loading only become serious when the current is large, for, as shown by Fig. 1 the variations in resistance and inductance are not appreciable for variations in current from zero to less than about .02 amperes.

In the case of a long conductor (by long is meant a conductor not necessarily long geographically but one having a great overall attenuation) the above objectionable characteristics resulting from loading would originate on the terminal sections only of a conductor. This is because the transmitted currents are rapidly attenuated and after traversing a length of conductor which may be a relatively small fraction of the total length they are reduced to such values that the variations in impedance resulting therefrom become negligibly small. The relative magnitudes of the currents in a typical submarine cable at various points along its length are shown in the curve of Fig. 2. This curve indicates that the current is reduced to less than half its original amplitude at a point about 200 nautical miles from the terminal and that at a distance of 500 miles the current is reduced to a value at which, referring to Fig. 1, the variations in the resistance and inductance of the loaded conductor may be neglected.

Since it is in the terminal portions only of a loaded cable that the objectionable characteristics of the loading arise, those portions of the conductor may be modified by making such changes as are necessary in the loading to reduce the variations in impedance, without materially increasing the desirable low overall attenuation due to the normal loading on the main portion of the cable.

There are several methods of reducing the impedance variations on the terminal sections. The simplest of course is to remove all the loading material and this may be desirable in some instances.

The preferred method in accordance with this invention, however, is to merely reduce the amount of the loading material on the terminal sections. This may be done by successive reductions in the amount of material at different distances from the terminal. Thus, as shown in Fig. 3 only a very thin layer of loading material may be used on the first section of the cable and the thickness of loading material increased on second, third and fourth sections until the fourth or central section is fully loaded. Fig. 3 discloses a cable arranged for duplex operation and in such a system the terminal sections having different degrees of loading are balanced by sections of artificial line having correspondingly different inductance and resistance characteristics.

The amount of loading material may be reduced in several ways. Where the material is applied to the conductor in the form of a single helical wrapping of tape or wire, the thickness of the tape or wire may be reduced. An alternative method, shown in Fig. 4, is to increase the space between successive turns. When the normal loading on the center portion of the cable is in two or more layers, the number of layers may be reduced on the terminal sections as shown in Fig. 5. Of course an alternative method is to reduce the thickness of the tapes without reducing the number of layers or to reduce both the thickness and the number of layers.

Ways of reducing the amount of loading material on the terminal section other than those suggested may of course be utilized. For instance the terminal section might be made up of alternate lengths of loaded and unloaded conductors, each length of conductor being short as compared to the length of the waves to be transmitted.

In general the reduction in resistance variations due to lighter loading is explained by the fact that the hysteresis losses are directly proportional to the amount of magnetic material employed. The impedance variations due to changes in the inductance are also less because the maximum inductance is reduced and the magnitude of the variations vary, to a limited extent at least, with the maximum values.

What is claimed is:

1. An inductively loaded signaling conductor having great overall attenuation and having continuously loaded sections in which the amount of the loading material per unit length of conductor is less on a section of said conductor adjacent an end thereof than on a section of said conductor more remote from the end.

2. A loaded signaling conductor having great overall attenuation and having continuously loaded sections, the quantity of loading material per unit length being relatively large in a portion of the conductors where the signaling current is small due to its having been attenuated by passage through a portion of the conductor and being relatively small in a part in which the signaling current is large.

3. A long submarine cable comprising a conductor surrounded by one or more helical wrappings of magnetic material, characterized in this that the thickness of said wrappings on a section of said cable adjacent an end thereof is less than the thickness of the wrappings on a section more remote from the end.

4. A submarine cable in which a section near a terminal thereof and a section near the center thereof are loaded with magnetic material, the loading being such that the flux density in the loading material produced by a given small current traversing the first

named section is the same as, but the total flux is less than, that produced in the loading material by an equal current traversing the second named section.

5 In witness whereof, I hereunto subscribe my name this 29th day of May, 1928.

JOHN J. GILBERT.
